UNITED STATES PATENT OFFICE

BENJAMIN S. NASH, OF SHORT HILLS, NEW JERSEY, ASSIGNOR TO THE STEARNS & FOSTER COMPANY, OF LOCKLAND, OHIO, A CORPORATION OF OHIO

DESIGN FOR TEXTILE FABRIC

Application filed July 24, 1929. Serial No. 32,175. Term of patent 7 years.

To all whom it may concern:

Be it known that I, BENJAMIN S. NASH, a citizen of the United States, residing at Short Hills, in the county of Essex and State of New Jersey, have invented a new, original, and ornamental Design for Textile Fabric, of which the following is a specification, reference being had to the accompanying drawing, forming part thereof.

In the drawing:—

The figure is a plan view of a piece of textile fabric showing my new design outlined in the rectangle indicated by the arrowed lines, the unit of the design being repeated in the relation indicated by the extensions beyond the unit-indicating lines.

I claim:

The ornamental design for textile fabric substantially as shown and described.

BENJAMIN S. NASH.
